US00D939528S

(12) **United States Design Patent** (10) **Patent No.:** **US D939,528 S**
Luxton et al. (45) **Date of Patent:** **** Dec. 28, 2021**

(54) **DISPLAY OR PORTION THEREOF WITH
GRAPHICAL USER INTERFACE**

(71) Applicant: **Apple Inc.**, Cupertino, CA (US)

(72) Inventors: **Joseph Mark Willoughby Luxton**, San Francisco, CA (US); **Alan C. Dye**, San Francisco, CA (US)

(73) Assignee: **Apple Inc.**, Cupertino, CA (US)

(**) Term: **15 Years**

(21) Appl. No.: **29/746,569**

(22) Filed: **Aug. 14, 2020**

(51) LOC (13) Cl. **14-04**

(52) U.S. Cl.

(57) **CLAIM**

The ornamental design for a display or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display or portion thereof with graphical user interface showing the claimed design; and, FIG. 2 is another embodiment thereof.

The broken lines in the figures show a display or portion thereof, and form no part of the claimed design.
